UNITED STATES PATENT OFFICE.

HERBERT B. TAYLOR, OF WESTFIELD, NEW JERSEY, ASSIGNOR TO HALL SWITCH & SIGNAL CO., A CORPORATION OF MAINE.

LIGHT-SIGNAL.

1,333,046.

Specification of Letters Patent.

Patented Mar. 9, 1920.

Application filed July 25, 1918. Serial No. 246,677.

To all whom it may concern:

Be it known that I, HERBERT B. TAYLOR, a citizen of the United States, and a resident of the town of Westfield, county of Union, State of New Jersey, have invented certain new and useful Improvements in Light-Signals, of which the following is a specification.

This invention relates to an improved construction and method of operation of light signals.

One object of the invention is to provide a mechanism which will operate to give three indications and which is arranged to normally give the danger or stop indication.

A further object is to provide a mechanism which is practically frictionless in operation.

Another object is to provide means whereby the mechanism will give a stop indication upon the failure of any of the operating mechanism.

Another object of the invention is to provide means whereby the mechanism is dead beat in operation to any position.

Further objects will be apparent from the appended description and claims.

Figure 1 shows the mechanism diagrammatically, partly in elevation and partly in section.

Fig. 2 is a section through a light signal showing how the mechanism may be utilized to control the indications of the same.

It has been the practice in signaling to utilize colored lights to give different indications to the engineer on the moving train as to the conditions of the track ahead, different colors being utilized to indicate different conditions. In order to avoid a false clear indication it is necessary that this type of apparatus should be so designed that upon failure of any part of the same a stop indication will be given to an approaching train. In order to accomplish this purpose when utilizing light signals, it has been the practice to consider the absence of light in the signal as a stop indication thereby obtaining the necessary protection against failure of the light.

The present apparatus has been designed with these ideas in mind.

Referring to the drawings there is provided a supporting member 1 which is adapted to carry at its extremities solenoid coils 2 and 3. Intermediate with the extremities

of supporting member 1 are clamps 4 and 5 which are adapted to support flexible ribbons 6 and 7 which may be made of thin strip metal or any other suitable material which will give the desired flexibility. At the extremities of the ribbons 6 and 7 is spectacle carrying member 8 suspended by means of clamps 9 and 10. The ribbons 6 and 7 are arranged to hang parallel with each other as shown in Fig. 1. Attached to either end of the spectacle carrying member 8 are solenoid cores 11 and 12 which are adapted to operate in conjunction with their respective coils 2 and 3. On the under side of spectacle carrying member 8 is attached an armature 13 so arranged that it will hang in operative relation to the pole pieces 14 and 15 of electromagnet 16. The source of energy 17 is provided to supply energy for the solenoid coils 2 and 3 and the electromagnet 16, also the signal light 18. Energy is continuously passing from source of energy 17 through wire 19, wire 20, magnet 16, wire 21, light 18, wire 22, wire 23, back to source of energy 17.

A three position relay 24 is diagrammatically shown for control of the apparatus. This relay may be of any of the well-known types, such as a direct current motor relay as disclosed in Patent #1180719 to W. K. Howe *et al.*, or an alternating current motor relay wherein energization of the windings in one direction will cause a contact finger to move in a certain direction and reversal of polarity will cause the finger to move in a reverse direction. The relay diagrammatically indicated at 24 is provided with a contact finger 25 which is normally adapted to maintain a neutral central position as shown. Upon the relay 24 being energized in one direction or the other the contact finger 25 will be caused to make contact with contact 26 or 27 respectively; it is obvious that this control may be obtained in any desired manner, for instance, a two way switch might be employed. It will be seen that on account of ribbons 6 and 7 being parallel and arranged with the broad faces parallel to each other that they will form a suspension for the spectacle carrying member 8 which will leave the same free to move laterally in either direction but will tend to resist any movement of spectacle carrying member 8 in a plane at right angles to this. The mechanism as shown is in the stop indicating po-

sition, and it will be seen that the spectacle carrying member is held centrally by means of the magnet 16 being energized through its circuit in series with lamp 18 and acting upon its armature 13 through its pole pieces 14 and 15. The object of magnet 16 is to insure centralizing the mechanism in its neutral position and it is obvious that should the circuit to this magnet fail the light 18 will be extinguished also thereby insuring the stop indication upon failure of the magnet. When in the neutral position the spectacle marked R will be at the axial center of the converging rays from the light 18 and it will be apparent that all the rays passing through this spectacle will be filtered and only those rays of the color of the spectacle will be allowed to pass through to give the desired color indication.

It will be seen by reference to Fig. 1 that the magnet 16 is continuously energized in series with the light 18. The energy passing through this magnet is so proportioned that it will be sufficient to arrest the movement of the moving spectacle-carrying member 8 but will not exert sufficient pull on its armature 13 to retain the member 8 in the central position shown against the pull of either solenoids 2 or 3 when one or the other is energized. Upon the energization of the relay 24 to move the contact finger 25 to the left, the following circuit will be closed. From source of energy 17, through wire 23, contact finger 25, contact 26, wire 28, solenoid coil 2, wire 19, back to source of energy 17. This will energize solenoid coil 2, causing it to draw its core 11 over to the left until the end of the core 11 strikes the supporting member 1. This will move the spectacle carrying member 8 over to the position indicated at 29 in dotted lines, moving the spectacle R out of the path of the rays and bringing the spectacle Y into the axial center of the rays, thereby giving another color light indication.

Upon the reversal of energy in the relay 24 contact finger 25 will be caused to move to the extreme right closing contact 27, closing a circuit from energy 17, through wire 23, contact finger 25, contact 27, wire 30, solenoid coil 3, wire 31, back to source of energy 17. This will energize solenoid coil 3 and on account of contact 26 being open solenoid coil 2 will be deenergized. The spectacle carrying member 8 will fall to its neutral position as shown in Fig. 1 by gravity thereby bringing the core 12 within the influence of solenoid coil 3 which will continue the movement of the spectacle carrying member 8 to the extreme right until core 12 strikes member 1 on this side. This will place the spectacle G in the axial center of light thereby giving a still further indication.

Upon the deenergization of relay 24 its

contact finger 25 will assume the central position as shown opening both contacts 26 and 27. This will leave solenoid coils 2 and 3 deenergized and the spectacle carrying member 8 will fall by gravity to its central neutral position being retained in this position from undue oscillation by means of magnet 16 acting on its armature 13.

It will be seen from the above description that by controlling the contacts 26 and 27 any desired indication may be given and that upon the opening of the control circuits magnet 16 will always centralize the spectacle carrying member 8 in its neutral position and tend to lock the same against undue oscillation which might be caused due to the pendulum action of spectacle carrying member 8 upon its ribbons 6 and 7.

From the above it can be seen that there is provided a signal mechanism which will give a plurality of different indications and although the mechanism is provided with a moving part it is so arranged that there are no rubbing surfaces of any kind to cause undue friction and stick the mechanism so that it will give false indications.

It is obvious that the form of construction shown can be modified without departing from the spirit of the invention, and that electromagnets with suitably arranged coacting armatures may be used in place of the solenoids shown in the disclosure.

What I claim is:—

1. In a signal mechanism a flexible suspension device, a movable member adapted to carry spectacles supported by said flexible suspension device, members attached to the movable member adapted to be influenced by electromagnetic flux, flux producing coils adapted to act on certain of said members to cause the movable member to move to either one side or the other, a flux producing coil adapted to act on another of said members to retain the movable member in a neutral position, a source of energy for said coils, and means for controlling the energization of the first mentioned coils whereby the movable member may be caused to assume different positions.

2. In a signal mechanism, a supporting member, a movable member adapted to carry spectacles, parallel flexible supporting strips adapted to suspend said movable member from said supporting member and to allow the movable member to move in one plane only, solenoid coils on said supporting member, coacting cores at either end of said movable member whereby the energization of one coil or the other will cause the movable member to be moved to one side or the other respectively, an armature carried by said movable member, an electromagnet adapted to coact with said armature to retain the movable member in a central position, a signal light, a source of energy, a closed circuit

through said signal light and said electromagnet in series whereby the light will be extinguished upon the opening of the circuit of the electromagnet, and means for controlling the energization of the solenoids whereby the movable member may be caused to assume different positions.

3. In a signal mechanism, a supporting member, a movable member adapted to carry 10 spectacles, flexible suspensions adapted to suspend said movable member from said supporting member, solenoid coils on said supporting member, coacting cores attached to said movable member to be moved to one 15 side or the other respectively, an armature carried by said movable member, electromagnetic means adapted to coact with said armature to retain the movable member in a central position, a signal light, a source of 20 energy, a closed circuit through said signal light and said electromagnetic means in series whereby the light will be extinguished upon the opening of the circuit of the electromagnetic means, and means for controlling 25 the energization of said solenoids whereby the movable member may be caused to assume different positions.
4. In a signal mechanism, a supporting member, a movable member adapted to carry 30 spectacles, flexible suspension means adapted to suspend said movable member from said supporting member, electromagnetic means carried by said supporting member, coacting devices attached to said movable member whereby the energization of one electromagnetic means or the other will cause the movable member to be moved to one side or the other respectively, another device carried by said movable member, electromagnetic means adapted to coact 35 with said other device to retain the movable member in a central position, and means for controlling the energization of the electromagnetic devices whereby the movable member may be caused to assume different positions.

one side or the other respectively, another device carried by said movable member, electromagnetic means adapted to coact with 40 said other device and retain the movable member in a central position, a signal light, a source of energy, a closed circuit through said signal light, and said electromagnetic means in series whereby the light will be 45 extinguished upon the opening of the circuit of the electromagnet, and means for controlling the energization of the first mentioned electromagnetic means whereby the movable member may be caused to assume 50 different positions.

5. In a signal mechanism, a supporting member, a movable member adapted to carry spectacles, flexible suspension means adapted to suspend said movable member from said supporting member and to allow the movable member to move without rubbing friction, electromagnetic means carried by said supporting member, coacting devices attached to said movable member whereby the energization of one electromagnetic means or the other will cause the movable member to be moved to one side or the other respectively, another device carried by said movable member, electromagnetic means adapted to coact 60 with said other device to retain the movable member in a central position, and means for controlling the energization of the electromagnetic devices whereby the movable member may be caused to assume different positions.

In testimony whereof, I have signed my name to this specification.

HERBERT B. TAYLOR.
